UNITED STATES PATENT OFFICE.

LEWIS O. CULVER, OF FORTYFORT, PENNSYLVANIA, ASSIGNOR OF ONE-THIRD TO
GEORGE W. CULVER, OF FORTYFORT, PENNSYLVANIA.

BOTTLE-CLOSURE.

1,259,606.

Specification of Letters Patent. Patented Mar. 19, 1918.

Application filed April 12, 1917. Serial No. 161,621.

To all whom it may concern:

Be it known that I, LEWIS O. CULVER, a citizen of the United States, residing at Fortyfort, in the county of Luzerne and 5 State of Pennsylvania, have invented certain new and useful Improvements in Bottle-Closures, of which the following is a specification.

My invention relates to improvements in 10 bottle closures, and it consists in the constructions, combinations, and arrangements herein described and claimed.

An object of my invention is to provide 15 a closure for a bottle which consists of a cap for a bottle which is pressed into position by a spring, suitable lever and link connections being joined therewith, whereupon by depression of certain portions of the link connections, the cap will be moved from the 20 mouth of the bottle and the pouring of the contents thereof permitted.

Another object of the invention is to provide 25 a device of the character described comprising a bottle having guard and hand receiving portions with which a depressible connection joined with certain link devices co-operates, said connection and link devices serving upon operation, to move a cap from the mouth of the bottle.

30 Other objects and advantages will appear from the following specification, reference being had to the accompanying drawing, in which:

Figure 1 is a side elevation of a bottle 35 illustrating the embodiments and application of my device, and

Fig. 2 is a front elevation of the bottle showing the parts illustrated in Fig. 1.

In carrying out my invention it will be 40 observed that a bottle 1 is utilized, the bottle 1 including the usual mouth 2. The bottle 1 is provided with a pair of guards 3 and 4. As will be observed in Fig. 2, the guards 3 and 4 are centrally channeled as at 45 5 thus providing the upstanding portions which properly constitute the respective guards.

The bottle 1 is somewhat depressed in the space between the guards 3 and 4 as at 6.

50 The hand or fingers of the user are adapted to engage the bottle at the depressed portion 6.

A band 7 is clamped or secured in any other suitable manner about the body 1 of 55 the bottle, and includes the ears 8 in which

a fulcrum pin 9 is fixed. A bell crank including a short arm 10 and a long arm 11 is fulcrumed on the pin 9 between the ears 8.

A second band 12 is clamped about the mouth 2 of the bottle 1 in any suitable manner, and includes the ears 13 in which a fulcrum pin 14 is likewise fixed. 60

A cap 15 is fulcrumed between the ears 13, and in order to effect the mounting of the cap 15, it is provided with an arm or 65 crank 15' which is suitably bent or formed that it may readily be received between the ears 13 as clearly shown in Fig. 1.

The cap 15 is normally forced into position upon the mouth 2 of the bottle 1, by a 70 pair of tension springs 16. The tension springs 16 are coiled about the fulcrum pin 14 and engage the cap 15 and the fulcrum pin 14 in such a manner that the normal closing of the mouth 2 through the medium 75 of the cap 15 is effected as above pointed out.

A link 17 is joined to the arm 15' of the cap 15, and the short arm 10 of the bell crank. A depressor 18 is connected to the long arm 11 of the bell crank and is disposed between the respective guards 3 and 4. The depressor 18 is curved at its lower portion as at 19, the tip of the curved portion being adapted to rest against the adjacent curved portion 19' of the body of the 85 bottle. The depressor 18 is thereby spaced from the bottle at the depressed place 6, and when the bottle is grasped by the hand and pressure is applied to the depressor 18, the various link connections are moved and the 90 cap 15 accordingly rocked upon its fulcrums 14, and thus the mouth is uncovered.

The operation and advantages of the bottle are as follows. It will at once be obvious 95 that in providing a closure of this character, that no matter how soiled one's hand or fingers might be, the mouth of the bottle will not become soiled as is always the case where a bottle is closed by a cork. Obviously in attempting to remove a cork from 100 a bottle the mouth thereof will be contacted by the fingers and thus become soiled. Diseases are not infrequently spread in this manner.

In the use of my device, the bottle 1 is 105 simply grasped at the place adjacent to the depression 6 whereupon the natural grip of the hand upon the depressor 18 will cause the bell crank including the long and short arms 11 and 10 respectively, to be moved 110

2
upon its fulcrum 9. The cap 15 will accordingly be rocked upon its fulcrum 14 against the tension of the springs 16 and thus uncover the mouth of the bottle. The contents 5 of the bottle may now be poured out and the danger of the contamination of such contents is entirely avoided because the mouth of the bottle was not touched by the hand.

While the construction and arrangement 10 of the device as described and illustrated, is that of a generally preferred form obviously modifications and changes may be made without departing from the spirit of the invention or the scope of the claims.

15 I claim:

1. In a device of the character described, the combination of a bottle having a mouth, a cap connected movably upon said mouth, an elongated depressor bar having an inwardly curved lower end said inwardly curved lower end bearing upon said bottle for spacing said depressor bar from said bottle, means for connecting said depressor bar to said cap, thereby allowing said depressor bar to be depressed inwardly toward said bottle when the bottle body is gripped, thus causing the cap to be moved to an open position.

2. In a device of the class described, the 30 combination of a bottle body having spaced guards projecting therefrom, said guards having aligned channels, said body having a depression between said guards, a closure removably mounted upon said bottle, a depressor bar fitting within said channels and projecting across said depression, means for connecting said depressor bar to said closure means, said depressor bar having a curved

lower end bearing upon said bottle body, thus causing said depressor bar to be normally spaced from said body, so that when 40 said bottle body is gripped the operator's hands will compress said depressor inwardly into said depression toward said bottle body, thus causing said closure means to be moved to an open position, and said guard holding 45 said depressor bar from side displacement when pressure is applied thereto.

3. In a device of the class described, the combination of a bottle body having a mouth thereon, a guide formed upon said body and having a central channel, said channel being curved to provide a curved lower portion upon said body, a closure means mounted upon said mouth, a depressor bar having an 50 inwardly curved lower end, means connecting the upper end of said depressor bar to said closure means, said curved lower end of said depressor bar bearing upon the curved 55 lower portion of said bottle body, thus causing said depressor bar to be spaced from said bottle body so that when the body is gripped said depressor bar will be pressed inwardly toward said body while said curved lower end will direct the depressor 60 bar downwardly to prevent accidental upward movement, thus causing said closure 65 means to be opened, and said guard holding said depressor bar against side movement when in operation.

70 In testimony whereof I affix my signature in presence of a witness.

LEWIS O. CULVER.

Witness:

M. E. JONES.
